Primary Examiner — John R Yeh*Assistant Examiner* — Dustin Andrew Griffith(74) *Attorney, Agent, or Firm* — Sandy Lipkin(57) **CLAIM**

The ornamental design for a storage box, as shown and described.

DESCRIPTION

FIG. 1 is a perspective view of a storage box, showing my design;

FIG. 2 is a front elevation view of FIG. 1;

FIG. 3 is a rear elevation view FIG. 1;

FIG. 4 is a left side view of FIG. 1;

FIG. 5 is a right side view of FIG. 1;

FIG. 6 is a top plan view of FIG. 1;

FIG. 7 is a bottom view of FIG. 1; and,

FIG. 8 is a bottom, rear, left perspective view thereof. The broken lines in the figures illustrate portions of the storage box, which form no part of the claimed design.

1 Claim, 8 Drawing Sheets(56)
